C. H. EPPLE.
ADVERTISING RACK.

(Application filed June 6, 1900.)

(No Model.)

UNITED STATES PATENT OFFICE.

CARL HENRY EPPLER, OF NEW YORK, N. Y., ASSIGNOR TO LOUIS EPPLER,
OF BOSTON, MASSACHUSETTS.

ADVERTISING-RACK.

SPECIFICATION forming part of Letters Patent No. 664,843, dated January 1, 1901.

Application filed June 6, 1900. Serial No. 19,316. (No model.)

To all whom it may concern:

Be it known that I, CARL HENRY EPPLER, a citizen of the United States, residing in New York, (252 Havermeyer street, Brooklyn,) in 5 the county of Kings and State of New York, have invented certain new and useful Improvements in Advertising-Racks, of which the following, taken in connection with the accompanying drawings, is a specification.

10 My invention relates to devices for displaying advertisements in frequented localities incidentally with reference-numbers, names, or other information relating to the use of certain appliances—as, for instance, telephonic 15 apparatus.

Each lessor of a telephone is likely to use certain calls frequently, and to avoid looking in the call-book each time the clerks often mark the walls, desks, and other convenient 20 spots with such calls. To avoid this, I have devised a rack to hold cards giving information as to day and night rates to certain exchanges, emergency calls—as fire, hospital, or police—advertisements of parties for long 25 terms permanently arranged in any selected portion of the panels, and readily-detachable holders placed in other panels to show frequent calls, preferably arranged alphabetically, the call being engraved on the holder or 30 a card secured in the holder.

The invention consists in a rack having panels for long-time advertisements, secured in some permanent manner, in connection with panels for telephone calls displayed in readily-detachable holders, and in the devices and 35 their combinations, that will be more particularly described.

The drawings show, in Figure 1, a front elevation of a rack; Fig. 2, a cross-section on the line xx of Fig. 1; Fig. 3, a detached vertical section on the line yy of Fig. 1; Fig. 4, an enlarged detail of the holder, latch, &c., on line zz of Fig. 1; Fig. 5, an enlarged rear view of the holder and latch; Fig. 6, an enlarged end view of the holder and latch; Figs. 45 7 and 8, views of the key.

In a good construction the rack consists of side bars a and a' , fastened to a back b and having rabbets c , forming grooves to hold advertising-cards d in the panels e and f , formed 50 by the vertical parting-beads g and h , the

cards being retained by an end bar i , secured by screws extending from the back. A horizontal parting-bead j forms, in connection with the vertical parting-beads g and h , in a 55 similar manner a wider panel k for advertising-cards.

Extending across between the side bars a and a' , at the top of the panels e and f , is the horizontal parting-bead l , above which the 60 vertical parting-beads m and n form, in the manner above described, panels o , p , and q , the middle one of which may retain cards for emergency telephone calls and the other two day and night rates for telephoning to various 65 places, the cards being secured by an end bar r , fastened by screws from the back.

Located between the beads g and h is the vertical bead s , forming the panels t and u for the more frequent telephone calls of the 70 subscriber. It is convenient to have these calls arranged alphabetically, and as calls are often added or changed it becomes desirable to easily interchange the cards having the call-numbers. For this purpose I place the 75 card v in a sheet-metal holder w , having ears A to retain the card and a tongue B at one end to enter a groove C in the vertical parting-bead s or h . When the holder is in position, the card is held back of the face of the 80 parting-bead, so that it may not be displaced. A latch D is pivoted at E to the back of the holder and is forced outward by a spring F . The latch has a beveled portion G , adapted when the holder is in position to snap into 85 recesses H in the parting-beads g and s . To easily remove a holder, the key I , having the thin sidewise-bent offset J , may be inserted between the holders and, coming in contact with the end of the latch, (which is stopped, 90 preferably, just short of the edge of the holder,) may unlock the holder and withdraw it from the panel.

Generous parties sometimes desire to give telephone subscribers so convenient a device, 95 and incidentally advertise their business, so they of course do not want their own card easily removed. For this purpose an end of a permanent panel may be used, as the additional horizontal groove makes it difficult to 100 put in a new card, even if the old holder can be removed. More particular persons may not

like to appear in the advertising-panels, and so it becomes convenient to have one holder, as K, supplied with a short latch L, requiring a special key adapted, perhaps, to enter a hole 5 in the latch to easily unfasten this holder against its stiffer spring.

Having described my invention, I claim and desire to secure by Letters Patent of the United States—

- 10 1. In an advertising-rack, panels to hold and display advertisers' cards in selected positions, associated with detachable latched holders for telephone calls, substantially as described.
- 15 2. In an advertising - rack, side and end bars, combined with vertical and horizontal parting-beads to form display - panels, the parts being provided with means to retain advertisers' cards and together with certain 20 detachable holders having devices to lock the

1 said holders in particular panels, substantially as described.

3. In an advertising-rack, a back having rabbeded bounding bars and parting-beads arranged to form grooves to securely hold 25 cards in panels, combined with holders for calls provided with tongues and latches adapted to interlock with certain of the grooves and recesses, so that they may be easily interchanged, substantially as described. 30

4. A holder having a locking-tongue and a latch, combined with ears to retain a card, substantially as described.

In testimony whereof I have hereunto subscribed my name this 4th day of June, A. D. 35 1900.

CARL HENRY EPPEL.
